DESIGN FOR AN ALL-WING AIRPLANE

John K. Northrop, Los Angeles, and Irving L. Ashkenas, Beverly Hills, Calif., assignors to Northrop Aircraft, Inc., Hawthorne, Calif., a corporation of California

Application April 23, 1946, Serial No. 128,896

Term of patent 14 years

(Cl. D71—1)

To all whom it may concern:

Be it known that we, John K. Northrop and Irving L. Ashkenas, citizens of the United States of America and residents of Los Angeles and Beverly Hills, respectively, county of Los Angeles, State of California, have invented a new, original, and ornamental Design for an All-Wing Airplane, of which the following is a specification, reference being had to the accompanying drawing, forming part thereof.

Fig. 1 is a three-quarter perspective view from above of an all-wing airplane in flight attitude, showing my new design.

Fig. 2 is a top plan view of the airplane;

Fig. 3 is a front view; and

Fig. 4 is a side elevational view of the airplane.

Fig. 5 is a bottom plan view of the airplane.

We claim:

The ornamental design for an all-wing airplane, as shown.

IRVING L. ASHKENAS.
JOHN K. NORTHROP.
